UNITED STATES PATENT OFFICE.

LESLIE McARTHUR, OF KENILWORTH, ILLINOIS, ASSIGNOR TO STEWART PHONOGRAPH CORPORATION, OF CHICAGO, ILLINOIS, A CORPORATION OF ILLINOIS.

PHONOGRAPH.

1,259,645.

Specification of Letters Patent. Patented Mar. 19, 1918.

Original application filed November 24, 1916, Serial No. 133,139. Divided and this application filed April 23, 1917. Serial No. 163,777.

To all whom it may concern:

Be it known that I, LESLIE McARTHUR, a subject of the King of Great Britain, residing at Kenilworth, in the county of Cook 5 and State of Illinois, have invented new and useful Improvements in Phonographs, of which the following is a specification, reference being had to the accompanying drawings, forming a part thereof.

10 This application is a division of my pending application, Serial No. 133,139, filed November 24, 1916.

15 The purpose of this invention is to provide an improved construction in certain details 15 of a phonograph or talking machine, so-called. It consists in the features and elements of construction shown and described, as indicated in the claims.

In the drawings:

20 Figure 1 is a detail side elevation of a portion of a phonograph comprising the tone arm and sound box mounted thereon, the same being shown in relation to the record with which the stylus on the sound box 25 coöperates.

Fig. 2 is a section at the line, 2—2, on Fig. 1.

Fig. 3 is a detail section at the line, 3—3, on Fig. 2.

30 Referring to the drawings:—The reproducer or sound box, A, carrying the stylus, B, is connected to the tone arm, E, by means of an elbow on the tone arm having an obliquely-extending arm, B¹, which is inter- 35 telescopied with an obliquely-extending arm, C¹, of the elbow, C, rigid with the sound box. The inclined elbow arms, B¹ and C¹, are mounted upon each other for relative rotation about their common axis, constitut- 40 ing a swivel connection between the tone arm and the sound box about whose axis the sound box may be adjusted from a position at which the stylus, B, may coöperate with a record, F, of the "zig-zag" type, to a posi- 45 tion at which it may coöperate properly with a record of the "hill-and-valley" type. For the purpose of rendering this joint snug and adapted to cause the sound box to remain safely at either position to which it is 50 adapted, and at the same time rendering said adjustment reasonable easy, the inter-telescopied parts at this joint,—said arms, B¹ and C¹,—are provided with recesses b¹

and c¹, at their inter-telescopied area, said recesses opening into each other and accom- 55 modating a bow-spring, D, having its middle part engaged in the recess in one of said members and its ends in the recess in the other member, and thereby reacting between the two members for holding the joint snug 60 and providing a frictional resistance to the relative rotation of said members. The recesses, b¹ and c¹, are circumferentially ex- 65 tended so that the aggregate amount of play of the spring lodged therein circumferen- 70 tially of the inter-telescopied members is the amount of the annular adjustment of the two members upon each other which is made for shifting the sound box from one of said operative positions to the other; and the 75 spring thereby, together with the recesses in which it is lodged, constitutes the means for limiting this adjusting movement of the sound box. This spring being a flat spring, and the recesses in which it is lodged being 80 channels in the respective members whose width is substantially that of the flat spring, said spring when engaged in the channels of the two members constitutes a key for re- 85 taining the two members together. It is 80 understood that the two members will be en- gaged with the key spring therein by first placing the spring in the recess in the inner member, its ends being lodged in said recess, and compressing the middle point or bow to 85 admit it into the other of said members, B¹, whereupon the two members being longi- 90 tudinally telescoped to their stop shoulders, the recesses, b¹, and c¹, being thereby regis- 95 tered with each other, the bow of the spring will snap into the recess, b¹, and the mem- bers will be locked together. That they cannot be disengaged is not an objection. In case of breakage of the spring, it will be preferable to substitute an entire new joint 95 rather than to undertake repairs. It may be considered desirable to provide for the locking together of the two inter-telescopied members, B¹ and C¹, and for limiting their relative rotation, not at one side only as by 100 the spring above described, but at the oppo- site side also, and for that purpose the more familiar expedient may be employed, con- 105 sisting of a pin, B², inserted from the out- side through the outer of said members after they are inter-telescopied with each other,

engaging a circumferentially-extending slot, c^2 , in the inner of said members, the extent of the slot being that of the annular adjustment of said members which is to be provided for.

I claim:—

1. In a phonograph, in combination with a sound box, a tone arm, elbows on the sound box and tone arm respectively, and a tubular joint at which said elbows are connected, comprising inter-telescoped arms of the elbow adapted for relative rotation about their common axis, having their inter-telescoped parts recessed, forming a cavity between them, and a bow spring lodged in said cavity, re-acting between said inter-tele-
- 10
- 15

scoped parts for frictionally resisting their relative rotation.

2. In a phonograph, in combination, a sound box tone arm, and a tubular joint at 20 which the sound box and tone arm are connected, comprising inter-telescoped members adapted to rotate relatively about their common axis, said members having at their inter-telescoped portions recesses forming a 25 cavity between them, and a spring lodged in said cavity, re-acting on both said parts for frictionally resisting their relative rotation.

In testimony whereof, I have hereunto set my hand at Chicago, Illinois, this 20th day 30 of April, 1917.

LESLIE McARTHUR.
